UNITED STATES PATENT OFFICE.

SIGMUND L. GOLDMAN, OF CHICAGO, ILLINOIS.

ELEVATOR.

991,148

Specification of Letters Patent.

Patented May 2, 1911.

Application filed November 4, 1909. Serial No. 526,169.

To all whom it may concern:

Be it known that I, SIGMUND L. GOLDMAN, a citizen of the United States, residing at Chicago, in the county of Cook and State of Illinois, have invented a new and useful Improvement in Elevators, of which the following is a specification.

My invention relates to certain new and useful improvements in elevators, and is 10 fully described and explained in the specification and shown in the accompanying drawings, in which:

Figures 1 and 1^a are side elevations of my improved elevator and the parts normally 15 placed adjacent thereto in operation, Fig. 1 representing the lower part of the elevator and Fig. 1^a the upper end thereof. Figs. 2 and 2^a are views taken in longitudinal section illustrating the lower and upper portions 20 of the elevator, respectively. Fig. 3 is a top-plan of the discharge-end of the lower gravity conveyer from which the articles carried pass on to the elevator; Fig. 4, a detailed perspective of a portion of the apparatus shown in Fig. 3, and Fig. 5, a top plan of the elevator, a portion of the side-rails being shown in section for the purpose of clearer illustration.

Referring to the drawings—A is the lower 30 end of a gravity conveyer comprising a frame-work and rollers upon which boxes, or similar articles may move by gravity in accordance with the practice which is now common.

A¹ is a discharge-slide which is pivoted 35 between its ends to the lower end of the gravity-conveyer, as illustrated in Figs. 1, 2, 3 and 4, from which it will be seen that the discharge-slide is so arranged that when in 40 its lower position, it will have its upper end projected into the path of the articles moving on the conveyer so as to stop their movement as shown in Fig. 1, and when raised to the position shown in dotted lines in Fig. 1, 45 will have its upper end so depressed as to permit their passage thereover. Downward movement of the discharge-slide beyond the position shown in solid lines in Fig. 1 is prevented by the engagement of projecting 50 ears *a* with fingers *a'* on the lower end of the conveyer.

B is the elevator frame-work which is 55 horizontal at its lower end, is provided with an intermediate curve and extends upward at an angle to any desired height, the same carrying at its lower and rear end a shaft *b*

and at its upper and forward end a shaft *b'*, upon which shafts are mounted sprocket-wheels over which run chains C. The chains are guided in channel-irons *b*² which run along both the upper and lower horizontal and curved portions of the conveyer and continue throughout the lower slanting portion thereof, and angle-irons *b*³ which extend along the upper portion of the slanting part of the conveyer frame, the said angles and channels being disposed at their flange ends, the angles having their flanges beneath the chains to prevent sagging thereof. At intervals along the chain C are located brackets which are opposite to each other upon the two chains and which said brackets are connected by cross-bars C¹, the brackets and cross-bars forming together flights for the propulsion of articles. Two links in advance of each of the brackets are a series of cross-bars C² lying in the plane of the chain and on the next preceding links are a series of flat cross-straps C³, C⁴, the links C³ carrying a series of forwardly projecting fingers C⁵, 80 the ends of which are curved downward as illustrated, and which are adapted to rest upon and be partially supported by the cross-straps C⁴. Shortly in advance of the cross-straps C⁴ are other cross-bars C⁶ also lying in the plane of the chains. The lower end of the conveyer-frame is provided with a series of straps D and D¹ extending longitudinally beneath the plane of the chains, and with their ends turned down as illustrated. The lateral chains C extend around the curve for a short distance and the central straps D¹ for a somewhat greater distance upward.

E is an upper conveyer, in form like the 95 conveyer A, so positioned as to receive articles delivered by the elevator in the manner to be explained.

The manner of operation of the entire structure is as follows: The parts normally 100 occupy positions as shown in Fig. 2, in which the boxes or cases on the conveyer A are arrested by the upwardly projecting end of the discharge-slide A¹. As one of the flights moves along, as to the position shown in dotted lines in Fig. 1, it raises the discharge-slide A¹ to the position shown in dotted lines in that figure, and the last box or case in the series moves onto the discharge-slide, sliding down the same after 110 the flight advances and permits the discharge-slide to drop into its original posi-

tion. Thus, after the passage of a flight past the discharge-slide one box or case will be found in an inclined position on the discharge-slide with its lower forward corner resting on the conveyer. The forward cross-bar, C⁶ in advance of the next following slide will catch said corner and drag the box forward to a certain extent permitting it to fall flat on the fingers C⁵ upon which it will move forward until said fingers are inclined by passing up the angular part of the elevator upon which the box will slip backward taking a position first like that shown by the rearmost box illustrated in dotted lines in Fig. 2 and finally, when the curve is completely past by the flight taking the position shown in dotted lines for the second box, after which the box or case occupies a fixed and definite relation with reference to the flight and fingers and may be carried for any distance upward without any relative movement between said parts.

It is to be noted that the surface immediately below the level of the chains is filled up more or less completely by the straps which extend upward to a point at which the box or case takes its final adjustment after which they are no longer necessary. When a box or case reaches the upper end of the elevator and the fingers C⁵ upon which it principally rests begin to turn with reference to the flight, the box moves through the various positions illustrated in Fig. 2, being finally discharged without shock or jar onto the upper conveyer as illustrated.

It is to be seen that the elevator thus described is simple and cheap in its construction, that its operation is certain and that the box or case is subjected to no considerable jars by which it or its contents might be injured. The construction as a whole is thoroughly efficient in operation and is free from the objections applying to many types of elevators particularly in that there is no opportunity for the box to be pinched between the flights and any projection either in the chain or its connection or on the elevator itself, as is the case with chain elevators and certain other types of construction.

I realize that considerable variation is possible in the details of construction of my improved device, without departing from the spirit of my invention, and I do not intend therefore to limit myself to the specific form herein shown and described.

What I claim as new, and desire to secure by Letters Patent, is—

1. The combination with a conveyer and a discharge-slide at the end thereof pivoted between its ends whereby its upper end can project into the path of articles on the conveyer, of an elevator provided with a chain and flights, the flights being adapted to raise

the discharge-slide in their passage to permit articles to pass thereover said discharge slide being adapted to support the articles while passing from the conveyer to the elevator.

2. In combination, a conveyer, a discharge-slide pivoted between its ends adjacent to the end of a conveyer whereby its upper end can project into the path of articles upon said conveyer, an elevator-chain provided with flights disposed beneath the discharge-slide, the flights being arranged to contact with the discharge-slide to elevate the same, depressing the upper end thereof to release packages moving upon the conveyer said discharge slide being adapted to support the articles while passing from the conveyer to the elevator.

3. The combination with a conveyer and an elevator adjacent thereto, of a discharge-slide swingingly connected to said conveyer and adapted when in lowered position to form a stop to retain articles thereon and when raised to form an incline down which such articles may travel to the surface of the elevator.

4. In combination, an inclined elevator for conducting packages upward and a conveyer inclined downwardly from a point adjacent the upper end of the elevator, said elevator comprising package-supporting separated flexible members free at their forward ends forming a slatted platform adapted to extend outwardly in the plane of the downwardly inclined conveyer at the curve of the elevator at its upper end, whereby packages resting on said flexible members are discharged from the elevator to the conveyer without substantial tilt or jar.

5. In combination, an inclined elevator for conducting packages upward and a conveyer inclined downwardly from a point adjacent the upper end of the elevator, said elevator comprising package-supporting separated flexible members free at their forward ends forming a slatted platform adapted to extend outwardly in the plane of the downwardly inclined conveyer at the curve of the elevator at its upper end and to partially bridge the space between the elevator and conveyer, whereby packages resting on said flexible members are discharged from the elevator to the conveyer without substantial tilt or jar.

6. In combination, elevator chains guided to travel first in a substantially horizontal and then in a diagonally upward direction for the elevation of packages, flights carried by the chains, and intermediate flat package-carrying members mounted at their rear ends on one link only of each chain and free at their forward ends, whereby said package-carrying members afford elastic carriers for the packages and are adapted to conform to the curve of the elevator chains at

the respective ends of the traverse of said chains, as set forth.

7. In combination, a chain guided to run first in a horizontal and then in an upwardly inclined plane, flights carried by the chain, 5 a pair of cross-bars extending between the chains, a series of longitudinally-extending flat-fingers carried by the rear-cross-bar and arranged to be supported by the forward cross-bar.

8. In combination, a chain guided to run first in a horizontal and then in an upwardly inclined direction, flights carried by the chain, a pair of cross-bars carried by 15 adjacent links of the chain, a series of longitudinally-extending flat fingers constituting a flat package-carrying platform supported by one of the cross-bars and arranged to rest on the other, and an additional cross-bar in front of said fingers, for the purpose set forth.

9. In combination, a conveyer-chain guided to run first horizontally and then upward at an angle, flights carried by the 25 chain, flat package-carrying platforms be-

tween the chains and in advance of the flights, a conveyer provided with a discharge-slide arranged to be contacted with by the flights, the upper end of the discharge-slide being arranged when the lower 30 end is depressed to project into the path of articles upon the conveyer.

10. In combination, a conveyer-chain guided to run first horizontally and then upward at an angle, flights carried by the 35 chain, flat package-carrying platforms between the chains and in advance of the flights, a conveyer provided with a discharge-slide arranged to be contacted with by the flights, the upper end of the discharge-slide being arranged when the lower 40 end is depressed to project into the path of articles upon the conveyer, and an additional cross-bar between chains in front of each platform.

SIGMUND L. GOLDMAN.
